DESIGN FOR AN OIL FILTER CASING

Eric Siemers, Kalamazoo, Mich., assignor to Rosee B. Lacey, Kalamazoo, Mich.

Application January 3, 1944, Serial No. 112,162

Term of patent 7 years

(Cl. D46—1)

To all whom it may concern:

Be it known, that I, Eric Siemers, a citizen of the United States, residing at Kalamazoo, in the county of Kalamazoo and State of Michigan, have invented a new, original, and ornamental Design for an Oil Filter Casing, of which the following is a specification, reference being had to the accompanying drawing, forming part thereof.

In the drawing:

I claim:

The ornamental design for an oil filter casing, as shown.

ERIC SIEMERS.
